SKI STORAGE RACK

Salvatore Laterra, Providence, R.I., assignor of a fractional part interest to Norma Hines, Attleboro, Mass.

Filed Apr. 9, 1973, Ser. No. 348,964

Term of patent 14 years

Int. Cl. D6—04

U.S. Cl. D6—130

FIG. 1

FIG. 2

FIG. 3

FIG. 4

FIG. 5

FIG. 6

FIG. 1 is a perspective view of a ski storage rack showing my new design, with a portion of a pair of skis shown in broken lines, which broken lines are for illustrative purposes only and form no part of the claimed design;

FIG. 2 is a front elevational view thereof;

FIG. 3 is a top plan view thereof;

FIG. 4 is a bottom plan view thereof;

FIG. 5 is a rear elevational view thereof; and

FIG. 6 is an end view thereof.

I claim:

The ornamental design for a ski storage rack, substantially as shown and described.
